(57) **CLAIM**

The ornamental design for a medical evaluation gateway housing, as shown and described.

DESCRIPTION

FIG. 1 is a perspective right view of a medical evaluation gateway housing in accordance with the present design; FIG. 2 is a perspective left view in accordance with the present design;

FIG. 3 is a front view thereof;

FIG. 4 is a back view thereof;

FIG. 5 is a right-side view thereof;

FIG. 6 is a left-side view thereof;

FIG. 7 is a top plan view thereof; and,

FIG. 8 is a bottom plan view thereof.

The broken lines shown in the drawings illustrate portions of the medical evaluation gateway housing that form no part of the claimed design.

1 Claim, 7 Drawing Sheets
